POWDER FILLING MACHINE

Charles J. Westin and Albert Donaghy, Sr., Philadelphia, Pa., assignors to F. J. Stokes Machine Company, Philadelphia, Pa., a corporation of Pennsylvania

Application October 12, 1934, Serial No. 748,047
Renewed September 28, 1937

10 Claims. (Cl. 226—99)

This invention relates to filling machines used for filling or packing powdered, pulverulent, or granular materials as well as viscous or pasty products into cans, cartons, jars, bottles, etc., and particularly to the kind of machines known as the volumetric type in which the product is measured out and discharged into the container by means of the intermittent rotation of an auger.

The object of our invention is to provide a new and improved machine of the single auger type which will be capable of accurately filling containers, without slopping over, at two to three times the possible speed of the old type of machines.

15 Some of the features of our invention consist in:

The novel arrangement of change gearing providing convenient means for adjusting the speed of the cam shaft so that this speed is maintained at one revolution for each fill, which is a speed suitable to the time cycle as determined by the capacity of the auger;

20 The convenient arrangement of cam-segments for adjusting and limiting the time of operation for the auger drive-clutch, which controls the amount of fill;

25 The conveyor chain drive, consisting of a Geneva gear co-operating with a double-arm driver, whereby a rapid, intermittent movement is imparted to the containers from station-to-station but at a slow retarded acceleration and deceleration, which prevents spilling or disturbing the loose powder in the containers;

The "two-step-fill" whereby the containers are 30 lifted under the auger in two stages or steps, allowing the air to freely escape from the container during the first two-thirds of the filling;

35 The no-container no-fill device, which only actuates the clutch controlling the auger rotation when a container is present to be filled;

40 The automatic lift-out for filled containers consisting in the channeled cups or container-holders co-operating with the take-off rails so that the containers are automatically lifted out 45 of the cups;

The automatic take-off comprising a spider with hinged arms for removing the containers from the lift-out in synchronized relation to the conveyor chain movement;

50 A slow-motion stirrer or agitator in the feed hopper to avoid whipping air into the powder;

The baffle in the feed hopper for maintaining a constant head of material around the auger and agitator;

55 Other features of our invention will be readily

apparent from the drawings and specification. In the drawings:

Fig. 1 is a side elevation of our device, with parts broken away, in vertical cross-section, and with parts of the conveyor and holders thereon omitted for the sake of clarity. 5

Fig. 2 is a front elevation of our device, with parts broken away, in vertical cross-section, and with parts omitted for the sake of clarity.

Fig. 3 is a perspective view in detail of a holder 10 with the cup and the can received therein.

Fig. 4 is a top plan view of our machine, with parts broken away, in horizontal cross-section.

Fig. 5 is a view in detail, in vertical cross-section, through the driving sprocket of the conveyor. 15

Fig. 6 is a top plan view of the driving mechanism, with parts broken away, in horizontal cross-section, and removed for the sake of clarity.

Fig. 7 is a view in detail in side elevation, with 20 parts in vertical cross-section, on the line VII—VII of Fig. 6.

Fig. 8 is a perspective view of the powder supply means and hopper.

Fig. 9 is a vertical cross section of the clutch-controlling lever return mechanism as viewed from the top of the sheet in Fig. 6. 25

In that embodiment of our invention chosen for description and for illustration in the drawings, our device is shown as consisting of a frame or support 1, on which all the other parts of the machine are mounted. On frame 1 is mounted a column 2, on which is supported the feeding bin or supply means 3, the hopper 4 beneath it, and the filling means or nozzle 5 depending therefrom. There is also mounted on column 2 a conveyor, generally indicated at 6, for the cans to be filled. Within frame 1 are mounted the main drive shaft 7, which is connected to a prime mover as by a pulley 11, the transverse 30 cam shaft 8, the clutch 9, the brake 10, the no-can no-fill device, the driving means for the conveyor 6 (best seen in Figs. 6 and 7), and the driving gears for the take-off spider 11 and the take-off disk 12 (best seen in Fig. 6). The 35 take-off disk 12 and the spider 11 are mounted on the top and to the rear of the frame 1, as is best seen in Figs. 1 and 4.

Powder-handling mechanism.—Referring now to Figs. 1, 2 and 8, the powder to be filled into the cans is placed in a supply means, or filling bin 3, having a bottom controlled by valve 13 (Fig. 2). From bin 3, when valve 13 is opened, powder flows into hopper 4 into a space partially confined by wall 14 and slide 15, which is ad- 55

justable by means of wing-nuts 16. Slide 15 can thus be set to maintain a suitable head of powder in the hopper 4. The hopper has an open bottom, to which is fastened filling means 5 or nozzle 5 as by clamp 17. As is best seen in Fig. 2, nozzle 5 has, at its lower end, a flange or collar 18 carrying an insert 19 of flexible material, such as felt, in its lower face and the container is pressed against this face when filling. Within the nozzle 5, and extending up into bin 4, is a filling auger 20, which is detachably secured to the end of auger shaft 21. As best seen in Fig. 8, auger-shaft 21 is driven through gear 34, from gear 26, on shaft 25. Gear 27 on shaft 28 is merely an idler for transmitting the power from gear 26 to gear 34. As seen in Fig. 6, shaft 25 is driven through gears 29 from shaft 30, which is driven from drive shaft 7, through clutch 9, and which is braked or stopped by brake 10 as soon as clutch 9 is released by control lever 46. Figs. 2 and 8 show a stirrer or agitator 31, which is rotatably mounted on sleeve 32, surrounding shaft 21, and thence on support 33, which is stationarily mounted on column 2. As is best seen in Fig. 8, sleeve 32 is driven through a worm gear 22, shaft 23 and gearing 24, connected to shaft 25. This gearing is so arranged that agitator 31 will rotate very slowly, usually at a speed of only 20 to 40 revolutions per minute, although shaft 25 imparts a speed of 500 to 700 revolutions per minute to auger-shaft 21. If the agitator 31 rotates too fast, the powder is whipped up and air is trapped in it causing variations in the amounts delivered by the auger. With most powders, the success of uniform fills depends upon the efficient removal of the air and the condensing of the powder into a uniform and dense mass. This is accomplished by the slow speed type of agitator.

No-can no-fill device.—Referring to Figs. 1, 2, 4 and 6, and especially Fig. 2, there is seen an arm or trip 35 adjustably mounted on shaft 36, so as to normally lie in the path of the containers carried by the conveyor, and readily turnable when the container passes the contact or index point. Shaft 36 carries, at its lower end, an arm 37 connected by a link 38 to a pivotally mounted clutch-locking arm 39. This locking-arm 39 normally overlies one end of the pivotally mounted clutch-lever arm 40, which, as is best seen in Fig. 6, carries at its other end a cam roller 41 co-operating with a cam 42 mounted on cam shaft 8. Referring to Fig. 1, there is connected to clutch-lever 40 a forked cross arm 46, which at one arm or fork has a spring 43 yieldably pressing roller 41 against the cam 42, and the other arm or fork is adjustable for proper control of the brake 10 and clutch 9 by bolt 146 and locking-nuts 147. Cross arm 46 is made in two parts, one of which is connected to clutch-lever 40 and the other of which is adjustable relative thereto by means of a screw-threaded bolt or the like and which serves to actuate brake 10 and clutch 9. Cam 42 is made up of several segments clamped to the hub on shaft 8 by screw 44. The segments are adjustable fan-like so that the length of time for the clutch-engagement can be made longer or shorter to suit the time required for the auger 20 in delivering the desired amount of powder. A pin or cam, for example, the inner end of screw 44 which projects beyond the back of cam 42, co-operates with the inner end of link 45 to return the trip 35 into the path of the container 75 between each step of the conveyor. As is best

seen in Fig. 6 in dotted lines, link 45 extends beneath clutch 9 and brake 10, so that the left-hand end of link 45 is in contact with the inner end of pin 44.

The operation of this device is as follows:—
A can, carried by the conveyor, turns arm 36, and consequently the linkage 35—36—37—38—39 thereby frees the end of arm 40. When roller 41 strikes a low portion of cam 42, arm 48 rises, rocking actuator 46, and thereby disengaging brake 10 and engaging clutch 9. This connects drive shaft 7 to stub shaft 30, whereby gears 29, shaft 25 and auger 20 are set in motion to measure the powder. Upon one revolution of cam 42, the high part of cam 42 raises roller 41, disengaging clutch 9 and applying brake 10. In the meantime, the pin 44 on the rear of cam 42 actuates linkage 45 and draws arm 38 again into position over lever 40, so that lever 40 cannot again rise until arm 38 is removed by the action of a container striking arm 35 as can be seen in Fig. 9.

Conveyor drive.—As seen in Fig. 6, drive shaft 7 turns gears 47 through worm-gearing 407, thereby driving cam shaft 8 at a constant rate of speed. This rate of speed, as will be explained later, is varied to suit the time required for filling a container. Figs. 6 and 7 show a double-armed Geneva-driver 48 for convenience of construction loosely mounted on shaft 8. The arms 48 cooperate successively in turn with one of the four slots 49 in Geneva star 50, which is rigidly mounted on shaft 51. It will be noted that the two arms 48 of the drive are placed 180° apart so that for each complete revolution of the driver two consecutive slots 49 of the Geneva star 50 are engaged by the arms 48 and thereby the Geneva star 50 given two successive motions of a quarter turn or 90° each, but the Geneva star 50 must only make one quarter turn in each cycle or during each rotation of the cam shaft 8. The driver is, therefore, operated at half the speed or so that it only makes one-half revolution to one of cam shaft 8. This reduced speed is obtained through the gear-train 80—81—83—84. On cam shaft 8 is fastened gear 80, which drives a gear 81 fastened on stub-shaft 82, to which is also fastened gear 83 which, in turn, drives gear 84 to which the driver with its two arms 48 is connected. The motion or quarter turn of the star 50 is transmitted through shaft 51, gearing 52, shaft 53 and sprocket 59 to the conveyor chain 62, imparting the proper step-by-step motion to it. Because of our novel arrangement of a double-armed driver in combination with the proper gearing, the speed of the conveyor chain is reduced to one-half, permitting us to operate the machine at twice the old production rate without disturbing or shaking out the contents of the filled containers. Referring to Figs. 4 and 5, keyed to shaft 53 is the hub 55, to which is fastened drive-disk 57. The disk 57 has slots 61 for bolts 68, so that the conveyor chain can be adjusted so as to place the containers centrally under the nozzle 5. The conveyor drive also has a safety device of the following construction: The sprocket 59 is supported between hub 55 and disk 57 so as to be free to turn. Disk 57, however, is provided with a perforated bushing 68 corresponding to a similar bushing 60 in sprocket 59. The power is transmitted from shaft 53 to the conveyor drive sprocket 59 by placing a shear pin, such as an ordinary wire nail of proper shearing strength, through the two bushings 68 and 60. If a con-

tainer should get caught anywhere along its travel, this shear pin will be cut and thus the drive and conveyor are protected from damage. Sprocket 59 drives chain 62 or other conveyor 5 which is guided by sprockets 63, 64 and 65 in an endless path, a portion of which passes adjacent to nozzle 5.

Can holder.—Referring to Figs. 1, 3 and 4, it will be seen that conveyor 62 carries a plurality of pins 66 thereon. Pins 66 pass through perforations 67 in the rear of the holders 68, each of which has in its front a projection 69 adapted to ride on a rail 70 which parallels the path of conveyor 62. Rail 70 is mounted by flanges 71 to the clamps 72, by which the conveyor is supported on column 2. Through one of the clamps 72 extends the adjuster 73, which bears at its lower end on the top of frame or support 1. It will thus be seen that, by loosening the bolts 74 which hold the clamps 72, the entire conveyor, indicated at 6, may be adjusted vertically on the column 2 by turning the adjuster 73. This adjustment permits the use of the machine with containers of varying heights.

A holder 68 is shown in Fig. 3. Into the cylindrical opening of holder 68 is slidably placed the cup or container-carrier 301, held in proper alignment by screw 303 fitting into slot 302. Two slots or notches 78 are provided in the wall 304 of cup 301 and made deep enough to permit the lift-out rails 96 (Fig. 4) to enter under the container C which normally rests on face 79. The wall 304 is made of suitable outline to properly hold the containers in place while being conveyed, and placed under the nozzle 5. At the filling station or nozzle 5, the cups are lifted by a two-step-motion of head 109 so as to bring the containers up to the flange 18.

Two-step fill.—Referring to Figs. 1, 2 and 6, it will be seen in Fig. 6 that cam shaft 8 carries a cam 99 thereon, which carries a plurality of faces adjustable by means 100. The faces of cam 99 are formed by the edges of segments which are adjustable fanwise, being held together by screws or bolts 100. The cam faces can be best seen in Fig. 6 which shows the faces at different distances from their center of revolution about axis 8. Roller 101 co-operates with cam 99 and is mounted on end of lever 102, which is pivoted on shaft 103 and carries a fork 104 at its outer end. Fig. 2 shows fork 104 co-operating with collar 105 fast on shaft 106, a spring 107 serving to press shaft 106 and lever 104 up so that the follower 101 will bear on cam 99. Shaft 106 carries a powder guard 108, thereby preventing the entrance of powder into the bearing of shaft 106 in the frame of support 1. Shaft 106 also carries a head 109 at its upper end, normally out of contact but underlying the path of holders 68 and cups 301. Upon movement of a low part of cam 99 beneath follower 101, spring 107 pushes fork 104 and shaft 106 up, so that head 109 lifts the holder 68, which is beneath outlet 5, into the position adjacent to, but spaced from, outlet or nozzle 5. Further movement of cam 99 brings a second and lower part of cam 99 under follower 101, permitting spring 107 to push shaft 106 and, consequently, the can carried in cup 301, yielding against the flexible pad 19 on flange 18 of outlet 5. At this point, the filling is completed. Cam 99 then lifts follower 101, moving fork 104 down, compressing spring 107, so that cup 301 returns to its seat on holder 68.

and head 109 is out of contact with cup 301, thus permitting movement of the next succeeding cup into position to be lifted by head 109. In the old machines, the containers C were either lifted directly in one step against the nozzle 5 or not lifted at all. When the container is lifted and clamped tightly against the nozzle flange at once, the air is trapped in the container and it is impossible to get the full amount into it. Then, when the container is released, the compressed air will carry with it an excessive amount of powder as it rushes out, causing waste of material and a very dirty machine. It also made it very difficult to get uniformly accurate fills. On the other hand, if the container is not lifted, the powder can only be filled loosely, as it is, of course, impossible to exert any pressure and pack the powder tightly into the container. We discovered that, by our method of a two-step fill, we could get rid of the air, fill and pack the container and obtain consistently uniform weight in the container. On the first step, the top of the container is brought within $\frac{1}{8}$ " to $\frac{1}{16}$ " of the felt pad 19, depending on the size of the container. Larger containers require larger space for a free escape of air, and still this space must not be too large as then the powder will slop over the sides. The air in the container is therefore replaced by loosely filled powder on the first step, which is then uniformly compressed by the additional powder forced in on the second step.

Automatic take-off.—Referring to Fig. 6, cam shaft 8 bears gear 80 fast thereon, which drives gear 81 on stub-shaft 82. Fast on shaft 82 is also gear 85 which drives gear 86 to which is fastened one of gears 87. Gears 87 drive spider shaft 88 in timed relation to the step-by-step motion of the conveyor. A pulley 89 is fast on shaft 88 and drives belt 90, pulley 91 and shaft 92 which rotates the take-off disk 12 at a speed sufficient to carry the containers away as they are delivered by the spider arm 94. Mounted on rail 10, adjacent a portion of the path of cups 301, are lift-out rails 96, which slope upward in the direction of movement of cups 301, and whose lower ends enter the slots 78 and pass beneath the bottom of the containers C in the cups 301 and raise the containers gradually out of the cups 301 into the path of one of the spider arms 94 which rise along the slope of the rails 96 and co-operate with the special stationary rail 97 to guide the containers onto disk 12. The spider arms are hinged at 95 to the spider hub on shaft 88, so that they will slide along the slope of the rails 96 up onto the disk 12. Previous to the invention of this device, it was necessary to have one or two operators stationed at this point for the purpose of removing the filled containers, which usually required considerable care in order not to spill any of the powder.

Change-gearing.—The weight or amount of powder that can be filled into a container within a certain time is basically controlled by the size and type of auger that can be used. A certain size container with a small opening may require three times as long for filling as a container of the same size with an opening twice the size, because the auger usually must be in proportion to the size of container opening. The old machines were designed so that the cam shaft 8 would operate at a constant number of revolutions per minute, usually 30, regardless of the time required for filling. That meant that in a case like the one mentioned above, where a con-

tainer could be filled in one-third the time, two-thirds of the operating time was wasted.

We have overcome this loss of efficiency by the novel use in powder filling machines of conveniently driving the cam shaft 8 through variable gear ratios. As described above, cam shaft 8 makes one revolution for each complete cycle of operation, which includes conveying, indexing, lifting the container, releasing the brake, engaging the clutch to start the auger, and, with the fill completed, disengaging the clutch and applying the brake. In order to accomplish the changeability of the cam-shaft speed, the shaft 8 was made independent of the gearing 407 on drive-shaft 7 and shaft 8 placed a suitable distance from stub-shaft 408 and the power transmitted from reduction gearing 407 through an interchangeable set of gears 47. When, therefore, a container can be filled in one-third the time, a suitable gear ratio is selected and proper gearing provided for train 47 to operate the cam shaft 8 at approximately three times the speed. It should be understood that almost any gear ratio may be used in providing a suitable number of revolutions of the cam-shaft 8. Thus, for example, the same machine may be operated for one size container at 20 filled containers per minute, at 30 for another size and 60 for still another size, etc.

30. The conveyor drive including the double-armed Geneva-driver is not claimed in this application as it is claimed in co-pending application of Francis J. Stokes and Charles J. Westin, Serial Number 461,884, filed 18th day of June, 1930.

35. We do not intend to be limited save as the scope of the prior art and of the attached claims may require.

We claim:—

1. In a powder-packing machine, the combination of, a conveyor for intermittently moving a plurality of cans to be filled, a plurality of holders horizontally fixed to said conveyor, a plurality of cups in said holders mounted for limited vertical movement, a guide rail adjacent to said conveyor, means on each of said holders for movably supporting said holders on said guide rail, and means for lifting each of said cups in succession during the filling operation.

2. In a powder-packing machine, the combination of, a conveyor for moving a plurality of cans to be filled, cups on said conveyor each having a notch in its upper surface, a take-off rail sloping upwardly in the direction of movement of said conveyor and mounted to enter the notch in each cup in succession, and means for conveying cans along said take-off rail after the cans have been released from the cups.

3. In a powder-packing machine, the combination of, a conveyor for moving a plurality of cans to be filled, cups mounted on said conveyor and each having a notch in its upper surface, and a take-off rail sloping upward in the direction of movement of said conveyor and mounted to enter the notch in each holder in succession.

4. In a powder-packing machine, the combination of, a conveyor for moving a plurality of cans to be packed with powder, a drive shaft for the movable parts of said machine, a stub-shaft mounted adjacent said drive shaft, gears connecting with said drive shaft and mounted on said stub-shaft, a cam shaft driven by said gears, a Geneva gear driver driven from said cam shaft, a Geneva gear driven by said driver, means for driving said conveyor from said Geneva gear, second means for supplying powder to said cans,

third means for driving said second means, a clutch for connecting said second means through said third means to said drive shaft, a brake for stopping said second means and said third means upon disconnection of said clutch, a lever controlling the operation of said clutch and of said brake, and a cam on said cam-shaft actuating said lever.

5. In a powder-packing machine, the combination of, a hopper for containing powder to be packed, an auger for feeding powder from said hopper, a conveyor for moving containers into which said powder is to be packed, a drive shaft for driving said auger and said conveyor, means including a stub shaft for driving said auger, a clutch for connecting and disconnecting said drive shaft and said stub-shaft, a brake for stopping said means when said clutch is disconnected therefrom, and a cam actuating said clutch and said brake, said cam having adjustable parts for varying the times of operation of said clutch and said brake.

6. In a can-filling machine, the combination of, a hopper for containing powder, an auger for feeding powder from said hopper, a conveyor for supplying beneath the hopper a plurality of cans to be filled, means for driving said conveyor and said auger, a clutch for connecting said auger to said means, a brake for stopping said auger immediately upon the disconnection of said clutch, and a no-can no-fill device comprising an arm pivotally mounted adjacent said conveyor on the oncoming side relative to said auger so as to be actuated by a can on said conveyor, a clutch-controlling lever actuated by said arm, a clutch lever connected to said clutch and to said brake so as to actuate one or the other and having a portion engaging said clutch-controlling lever in one position thereof and free of said clutch-controlling lever in another position thereof, a cam actuating said clutch lever when said clutch lever is free from said clutch-controlling lever, a spring stressing said clutch lever against said cam, and means actuated by said cam for restoring said clutch-controlling lever to locking position after it has been moved to disengaged position by said arm.

7. In a can-filling machine, a hopper for containing powder to be fed, an auger for feeding powder from said hopper, a drive-shaft for driving the moving parts of said machine, connections between said drive-shaft and said auger, a clutch controlling the connection of said connections to said drive-shaft, a brake for stopping said connections and said drive-shaft upon disconnection of said clutch, a clutch-lever actuating said clutch and said brake in interlocking relation, a cam driven from said drive-shaft, a spring stressing said clutch-lever against said cam, a no-can no-fill device located so as to be actuated by the cans to be filled, a clutch-controlling lever actuated by said no-can no-fill device and located so as to be movable into and out of a portion of the path of said clutch-lever thereby controlling the movement of said clutch-lever towards and away from said cam in response to the position of said no-can no-fill device, and means for moving said clutch-controlling lever in the opposite direction to that caused by said no-can no-fill device to free said clutch-lever from the control of said clutch-controlling lever.

8. In a can-filling machine, a hopper for containing powder to be fed, an outlet for powder for said hopper, first means for feeding powder from said hopper through said outlet, a conveyor

for conveying a plurality of cans to be filled with said powder adjacent said outlet, and second means operating simultaneously with said first means for lifting each of said cans in succession from said conveyor so as to hold the lifted can adjacent to but spaced from said outlet during the initial part of said lifting so as to provide an outlet for air from said can and for lifting said lifted can into contact with said outlet during a latter part of the lifting of said can.

10. 9. In a can-filling machine, a hopper for containing powder to be fed, an outlet for powder from said hopper, first means for feeding powder from said hopper through said outlet, a conveyor for conveying a plurality of cans to be filled with said powder adjacent to said outlet, second means for lifting each of said cans in succession from said conveyor under said outlet, and a cam having three different actuating parts, one of said parts being arranged so as to hold said second means away from said conveyor, another of said parts being arranged so as to cause said second means to lift each of said cans in succession into a position adjacent to but spaced from said outlet to provide an outlet for air from said lifted can during the first part of the operation of said first means, and said third part being arranged to cause said second means to lift said can into contact with said outlet during a latter part of the operation of said first means.

10. In a can-filling machine a hopper for containing powder to be fed, a nozzle forming an outlet for powder from said hopper, an auger for feeding powder from said hopper through said nozzle, a conveyor for moving a plurality of cans to be filled adjacent to said nozzle, a rod mounted in alignment with said nozzle so as to remove each of said cans in succession from said conveyor and to lift said can onto said nozzle, a spring stressing said rod toward said nozzle, a lever having engagement with said rod, and a cam having engagement with said lever and having three actuating parts, one of said parts being arranged to hold said lever in position to compress said spring and hold said rod away from said conveyor, another of said parts being adapted to provide for partial expansion of said spring to raise each of said cans in succession from said conveyor into a position adjacent to but spaced from said nozzle so as to provide an outlet for air from said lifted can during the initial part of the operation of said auger, and said third part being adapted to free said rod from the control of said lever so that said spring presses said rod and thereby presses the lifted can on said rod into engagement with said nozzle during a latter part of the operation of said auger.

CHARLES J. WESTIN.

ALBERT DONAGHY, SR. 30
